(57) **CLAIM**

The ornamental design for a liquid container with suspended surface, as shown and described.

DESCRIPTION

FIG. 1 is an upper perspective view of a liquid container with suspended surface showing the new design;

FIG. 2 is a left side elevation view thereof;

FIG. 3 is a right side elevation view thereof;

FIG. 4 is a rear side elevation view thereof;

FIG. 5 is a front side elevation view thereof;

FIG. 6 is a top plan view thereof;

FIG. 7 is a bottom plan view thereof; and,

FIG. 8 is a section view thereof taken along line 8—8 of FIG. 6; and,

FIG. 9 is a lower perspective view thereof.

The features illustrated in broken lines in the figures do not form a part of the claimed invention.
